(No Model.)

C. A. LITTLEFIELD.
HEDDLE FOR CROSS WEAVING.

No. 363,072.

Patented May 17, 1887.

UNITED STATES PATENT OFFICE.

CHARLES A. LITTLEFIELD, OF FALL RIVER, MASSACHUSETTS, ASSIGNOR OF ONE-HALF TO ELIAS A. TUTTLE AND JAMES T. MILNE, BOTH OF SAME PLACE.

HEDDLE FOR CROSS-WEAVING.

SPECIFICATION forming part of Letters Patent No. 363,072, dated May 17, 1887.

Application filed March 14, 1887. Serial No. 230,837. (No model.)

To all whom it may concern:

Be it known that I, CHARLES A. LITTLEFIELD, a citizen of the United States, residing at Fall River, in the county of Bristol and State of Massachusetts, have invented certain new and useful Improvements in Heddles for Cross-Weaving; and I do hereby declare the following to be a full, clear, and exact description of the invention, such as will enable others skilled in the art to which it appertains to make and use the same.

My invention consists of a peculiar combination of metallic half-heddles, which is designed to serve the purposes for which dousps are now employed in cross-weaving, and at the same time be as effective in operation and more durable.

In operating with my half-heddles it is necessary to have at least three heddle or harness frames of the pattern now in use for supporting the common form of wire heddles well known to those skilled in the art of weaving. The middle frame is supplied with a specially-shaped half-heddle or needle formed of properly twisted wire or stamped from any suitable sheet metal. When the needle or half-heddle is made of wire, the latter is twisted in such a manner as to form an eye at the top end, through which passes the warp thread or threads required to produce the desired effect in the pattern woven. Below the twist which forms the eye the wires are separated in such a manner as to form a continuous slot or loop from near the eye to a point at or near the lower end, where the half-heddle is formed with an eye or loop adapted to receive the bar upon which the half-heddle is strung, only a single bar being used for the support of the said half-heddle. Through the long slot or loop are passed other looped wires, forming half-heddles, there being two of this description to each one of the first named. These wires are secured, one on the right the other on the left, to the two outside heddle-frames at the top, being strung on the ordinary cross-bars of the said frames, the latter passing through suitably-sized loops at the top ends of the said looped wires.

To produce the desired pattern the thread which is to be twisted or crossed about its ad-

jacent thread should be drawn through the eye at the top of the lower half-heddle, and the thread or threads about which it is to cross should be drawn in between the two upper loops or half-heddles and in line with the 55 thread passing through the lower heddle-eye. When the harnesses are in a state of rest, the warp-line is established so as to bring the yarn passing through the lower heddle-eye to a position from which it can be drawn up at the 60 forming of the shed upon the desired side of the yarn about which it is to be turned or twisted. The crossing is effected by alternately operating the heddle-frames to which the upper half-heddle or looped wires are secured, the shed being formed by lifting the harness or shaft to the right or left of the frame to which the half-heddles or needles are secured at the bottom. The upper looped wire not lifted slides easily down the long slot or 65 loop in the lower half-heddle, the latter and the upper half-heddle to which the lifting-power is applied being drawn into line, thus forming a guide for deflecting the thread about which the crossing or tie is formed to the 70 desired side of the needle or lower half-heddle.

It will be readily understood by those skilled in the art of weaving that by multiplying the number of harnesses I am able to produce any design or pattern that can be produced by the 80 use of dousps or similar appliances, at the same time having a far more serviceable and efficient substitute.

I have illustrated my invention by the accompanying drawings, in which Figure 1 is a 85 front view of portions of a set of heddle-frame bars with my invention applied thereto. Fig. 2 is a view representing in vertical section the bars of the heddle-frame and showing the position of the yarns before the crossing takes 90 place. Fig. 3 is a similar view showing the half heddles after the crossing takes place. Figs. 4 and 5 are front and side views, respectively, of a modified form of the lower half-heddle or needle.

Similar letters refer to like parts.

Upon the lower bar, *a*, of the central heddle-frame are strung the upright needles or half-harnesses *D*, which, in the form shown in Fig. 1, are made of ordinary-sized heddle-wire, 100

formed at the top with an elongated eye, *d*, by 1
a return and twist of the wire after the manner
of making the common metallic heddle. Below
the eye *d* the half-heddle *D* is formed
5 with a long loop or opening, *D'*, and at the
lower end thereof the said half-heddle is formed
with a single eye or loop adapted to receive
the lower bar *a* of a harness-frame.

Depending from the two harness-frames, at
10 each side of the central bar *a*, are the two half-
heddles or wire loops *K* and *H*, respectively,
which engage the long loop *D'* of the vertical
needle *D*. The half-heddles *H* and *K* are
formed at their upper ends, as shown, with
15 eyes or loops to receive the upper bars, *eb*, of
the appropriate harness-frames. In the form
of my devices represented in Figs. 1 and 2 of
the drawings the various loops or eyes in the
half-heddles are all made by twisting the wires,
20 as usual in the manufacture of wire heddles.

When it is desirable to weave with heddles
like those described and shown, the threads *m*,
or those which are to twist around the adjacent
25 warp-threads *n*, are passed through the
eye *d*, and the movements of the harness-frame
b and *e* alternately produce the crossing or the
tie. The vertical needle or half-heddle *D* being
30 always engaged with the two upper looped
half-heddles *K* and *H*, whenever either of the
latter is raised said needle or half-heddle *D*
is lifted, with its warp-thread *m*, upon the
proper side of the other warp-thread, *n*, to the
proper height to form the shed, the inactive
35 harness, with the half heddles *K* or *H*, as the
case may be, remaining stationary, and the
half-heddle thus left inactive being guided in
the loop of the vertical needle *D*, as shown
clearly in Fig. 2 of the drawings.

A modified form of needle, which for some
purposes is preferable, is shown in Figs. 4 and 40
5, it being formed from sheet metal, provided
with a central partition of solid metal, *s*, and
having slots *s's'*, one to each side, constituting
suitable guides for the depending connecting-
links or half-heddles *K* and *H*, and an open-
ing, *S''*, for the reception of the bar of the har-
ness-frame *a*.

I claim—

1. The combination, with the half-heddles *K*
and *H*, of the half-heddle or needle *D*, having
50 an opening, *S''*, in the lower part to receive
the heddle-bar and formed with a central par-
tition, *s*, slots *s's'*, at each side of said partition,
for receiving the half-heddles *K* and *H*, and an
eye at the upper end for the reception of the 55
yarn, all constructed, arranged, and operated
as set forth.

2. The combination of the three half-hed-
dles *D*, *H*, and *K*, the two upper outside half-
heddles, *K* and *H*, each being formed, as shown, 50
with two separate loops, one for the reception
of the heddle frame-bar, the other being inter-
locked with the lower half heddle, *D*, and the
said half-heddle *D* being formed with a warp-
eye, *d*, a single loop to receive a supporting-
bar, and an intermediate opening or openings
65 to receive the loops of the half-heddles *H* and
K, all arranged and constructed as described,
and for the purpose set forth.

In testimony whereof I affix my signature in 70
presence of two witnesses.

CHARLES A. LITTLEFIELD.

Witnesses:

JAMES T. MILNE,
E. A. TUTTLE.
